UNITED STATES PATENT OFFICE

FRANK A. FAHRENWALD, OF CHICAGO, ILLINOIS

METALLURGICAL FURNACE

Application filed June 17, 1929. Serial No. 371,613.

My invention relates to metallurgy, and includes among its objects and advantages a decrease in upkeep expense and improved fuel economy in the operation of conveying equipment and furnaces of the types commonly employed for the heat treatment of metals.

In the accompanying drawings:

Figure 1 is a partly diagrammatic longitudinal section of a furnace according to the invention.

10 Figure 2 is a section on line 2—2 of Figure 1, and

Figure 3 is a side elevation of the power transmission.

15 In the embodiment of the invention selected for illustration, the furnace comprises the usual chamber 10. Heat may be generated inside the chamber by the usual flame projecting devices throwing flames through openings 12, the products of combustion being allowed to leak or flow out of the chamber gently at the charging and delivery openings, or mouths.

Conveying

25 To subject an object to heat treatment in such a furnace, it is inserted at one end of the chamber and conveyed slowly to the other end where it is removed. I have illustrated a conveyor made up of a chain or strand 14 running over sprockets 16, with its upper reach supported by a guide 18, over which the strand slides. This makes it possible to give each piece of metal substantially identical heat treatment with every other piece by 30 putting all the pieces in at one end and taking them out at the other. The time of exposure may be determined over a wide range by varying the speed of the strand.

40 The strand 14 is made of an alloy having high strength and corrosion resistance at high temperatures, for example, an alloy containing 16% chromium and 35% nickel, and the balance iron with the customary steel 45 containing percentages of carbon, silicon and manganese. Where the products of combustion or the material being handled introduce material quantities of sulphur I prefer to employ an alloy containing more than 25% 50 chromium and less than 10% of nickel, be-

cause the higher percentages of nickel are accompanied by susceptibility to corrosion by sulphur-containing compounds.

The operating temperatures I employ are all in a range where ordinary steel and cast 55 iron have insufficient physical strength or resistance to chemical reaction with the gases or other materials present to be capable of use.

I have designated the charging, or receiving 60 end 20 and the delivery end 22. The sprockets 16 are both within the chamber, so that all parts of the chain and sprockets remain continuously throughout a run at the temperature prevailing inside the chamber, 65 and are only cooled and reheated when the outfit is shut down.

The temperatures employed in many such 70 chambers are limited only by the ability of the conveyor to endure them. Recent improvements in this art call for temperatures from 1700 to 2000 degrees, Fahrenheit, in order to impart the desired quality to the treated product. At such temperatures the mechanical strength of the best available 75 metal is reduced to a point where the weight of the conveyor per unit length may approximate or even exceed the weight of the material carried by it. The heat lost by conveyor metal moving out of the chamber is saved 80 by keeping the strand inside, and at such high temperatures this saving is a substantial fraction of the heat required to run a furnace.

At such extreme temperatures, also, the repeated 85 heating and cooling of the strand becomes a factor in determining the life of the strand, of substantially as much importance as any other, not excluding the usually dominating feature of mechanical wear. Keeping the strand inside substantially eliminates this item.

Charging and delivering

When the material to be treated is in the 95 form of a large number of small pieces, the chain links may be provided with carrying pans or trays 24. The material may be poured in continuously or at frequent intervals down a stationary chute 26, and received 100

when it falls off the conveyor on a similar chute 28 which may guide it directly into a quenching bath 30.

When the material is in pieces of a size calling for individual handling, the new stock may be brought up to the charging mouth on a roller conveyor 32 and pushed off the charging conveyor 32 on to the furnace conveyor. I have illustrated sectional metal rails 34 embedded in the upper surface of the lower wall 36 defining the charging mouth. The entering piece, when it is too short to bridge the gap between the roller conveyor and the furnace conveyor, may slide a little on these rails instead of on the refractory material of the wall 36.

At the delivery end, pieces calling for individual handling may be similarly pushed along over rails 38 onto a receiving conveyor 40.

With either large or small pieces, most of the charging and delivery mouths should be covered to hold the heat. I have illustrated cover plates 42 of refractory material. When the operation is continuous, an orifice just large enough to provide reasonable clearance for the stream of material may be left open at each end. In the case of a furnace, it is not difficult to fire the furnace in such a way that the flow of the products of combustion out through such orifices will prevent heat loss other than the always unavoidable radiation loss.

When the charging and delivery are intermittent, the guide chutes 26 and 28 may be withdrawn and the covers 42 may be moved out of the way each time a piece is to be inserted or removed.

Drive

I have illustrated transverse shafts 48 which may be of the type disclosed in my Patent 1,623,469 of April 5, 1927, and have end bearings 50 for the shaft at the delivery end, and 52 for the shaft at the receiving end. The bearings 50 are fixed and stationary, but the bearings 52 are slidably mounted on supports 54 and may be adjusted longitudinally of the furnace by suitable means, such as rods 56 provided with adjusting turn-buckles 58 anchored at 60 to any suitable stationary anchorage. This adjustment means makes it possible to keep the amount of slack in the chain properly adjusted. When the chain is hot it should run in some such position as indicated in Figure 1, with the weight of most of its lower reach carried by the track 44, and the turn-buckles may be adjusted to secure the proper operating condition. Whenever the furnace is shut down and the chain cools, the thermal contraction will shorten the chain and lift somewhat more of the return reach of the chain off the track 44. This will somewhat increase the tension in the chain, but at the lower temperatures

prevailing, the strength of the chain increases much more rapidly than the tension.

The main item of tension in the chain is that developed by dragging the load over the skid 18. A serious addition to this tension would be the tension developed in dragging the return reach 46 over the skid 44.

When hot and loaded the heaviest tension in the chain will be at the point 62 just before the chain rides on to the sprocket 16 at the delivery end. To reduce the load at this point as much as possible it is desirable to turn the sprocket at the receiving end with enough force to carry all the tension load of the return reach 46. In many instances the links of the conveyor 14 are so designed that they will stand quite a little pushing or compression load and when this is the case, it is possible to relieve the load at the point 62 still further by pushing a little on the chain at the receiving end to carry a material fraction of the friction load on the track 18.

I have indicated a worm wheel 64 and worm 66 for delivering power to the shaft 48 at the delivery end. Sprockets 68 on the shafts 48 are engaged by a cold chain 70 outside the furnace. The upper reach of the chain 70 transmits power to the shaft 48 at the receiving end and is automatically maintained under constant predetermined tension by passing this reach of the chain over fixed idlers 72 and under a floating idler 74 carrying weights 76 hung on a clevis 78. In this way, by properly adjusting the weights 76, the force applied to the sprockets at the receiving end is maintained substantially constant, regardless of the speed, and may be adjusted by varying the weights at 76, to any desired value.

Without further elaboration, the foregoing will so fully explain the gist of my invention that others may, by applying knowledge current at the time of application, readily adapt the same for use under various conditions of service.

I claim:

1. High temperature equipment comprising a hot chamber; an endless strand of heat resisting alloy in said chamber; said chamber enclosing all of said strand; said strand including carrying means adapted to receive and support either individual large pieces of material or a stream of small pieces of material; said chamber having an intake mouth and a delivery mouth adjacent the ends of said strand; charging means at the intake mouth for delivering streams of small pieces of material, or for intermittently charging individual large pieces of material far enough through said mouth to get onto said strand; and receiving means for getting material carried through said furnace by said strand out through said delivery mouth.

2. High temperature equipment comprising a hot chamber; transverse shafts inside

- said chamber at the ends thereof; an endless conveyor strand of heat resisting alloy passing around both shafts; a track for each reach of said strand on which said strand 5 may slide; a first power transmission for driving the shaft at the delivery end of said strand; a second power transmission for delivering power to the shaft at the receiving end of said strand; means for adjusting the 10 transmission to the receiving end to deliver a predetermined force or torque; and automatic means for maintaining said force or torque constant; said second power transmission being driven from said first power transmission. 15
3. High temperature equipment comprising a hot chamber; transverse shafts inside said chamber at the ends thereof; an endless conveyor strand of heat resisting alloy passing around both shafts; a track for each reach of said strand on which said strand 20 may slide; a first power transmission for driving the shaft at the delivery end of said strand; a second power transmission for delivering 25 power to the shaft at the receiving end of said strand; means for adjusting the transmission to the receiving end to deliver a predetermined force or torque; and automatic means for maintaining said force or torque constant. 30
4. High temperature equipment comprising a hot chamber; transverse shafts at the ends thereof; an endless conveyor strand of heat resisting alloy passing around both shafts; a track for each reach of said strand 35 on which said strand may slide; a first power transmission for driving the shaft at the delivery end of said strand; a second power transmission for delivering power to the shaft at the receiving end of said strand; and 40 means for adjusting the transmission to the receiving end to deliver a predetermined force or torque. 45
5. High temperature equipment comprising a hot chamber; transverse shafts; an 45 endless conveyor strand of heat resisting alloy extending across said chamber and passing around both shafts; a track for the upper reach of said strand on which said strand may slide; a first power transmission for driving 50 the shaft at the delivery end of said strand; a second power transmission for delivering power to the shaft at the receiving end of said strand; and means for adjusting the transmission to the receiving end to deliver a 55 predetermined force or torque. 60
6. High temperature equipment comprising a hot chamber; transverse shafts inside said chamber at the ends thereof; an endless conveyor strand of heat resisting alloy passing around both shafts; a track for the upper reach of said strand on which said strand may slide; a first power transmission for driving the shaft at the delivery end of said strand; a second power transmission for delivering power to the shaft at the receiving 65 end of said strand; and means for varying the distance between the shafts to take up slack without interfering with said torque adjustment. 70
7. High temperature equipment comprising a hot chamber; an endless conveyor strand of heat resisting alloy having a load carrying reach in said chamber; power means for exerting tension on said strand at the delivery end of said load carrying reach to pull said reach and the load thereon through 75 said chamber; additional transmission for delivering power to said strand at the receiving end of said reach; and an automatic load control means for said additional transmission for maintaining the power delivered 80 at the receiving end sufficient to carry all the strand load up to that point, plus an additional increment to push on said load carrying reach at the receiving end. 85
8. High temperature equipment comprising a hot chamber; an endless conveyor strand of heat resisting alloy having a load carrying reach in said chamber; power means for exerting tension on said strand at the delivery end of said load carrying reach to 90 pull said reach and the load thereon through said chamber; additional transmission for delivering power to said strand at the receiving end of said reach; and means for adjusting said additional transmission to carry 95 all the strand load up to that point, plus an additional increment to push on said load carrying reach at the receiving end. 100
9. High temperature equipment comprising a hot chamber; transverse shafts inside said chamber at the ends thereof; an endless conveyor strand of heat resisting alloy passing around said shafts; a track for the upper reach of said strand on which said strand 105 may slide; a first power transmission for driving a shaft at the delivery end of said strand; a second power transmission for delivering power to a shaft at the receiving end of said strand; means for adjusting the 110 transmission to the receiving end to deliver a predetermined force or torque, and means for varying the distance between the shafts to take up slack without interfering with said torque adjustment. 115
10. High temperature equipment comprising a hot chamber; transverse shafts inside said chamber; an endless conveyor strand of heat resisting alloy passing around both shafts; a track for the upper reach of said strand on which said strand may slide; a first power transmission for driving a shaft at the delivery end of said strand; a second power transmission for delivering power to 120 a shaft at the receiving end of said strand; means for adjusting the transmission to the receiving end to deliver a predetermined force or torque; and means for varying the distance between the shafts to take up slack 125 130

without interfering with said torque adjustment.

11. High temperature equipment comprising a chamber; an endless conveyor strand of heat resisting alloy having a load carrying reach extending longitudinally of said chamber; means acting on said strand for pulling said strand along; and additional means engaging said strand at a point back of said first means for pulling on said strand to lessen the load on said first means.

12. High temperature equipment comprising a heated chamber, movable conveyor means inside said chamber, movable conveyor means outside said chamber, said chamber having a heat retaining wall between the movable conveyor means inside and outside, said heat retaining wall having an aperture for the passage of material therethrough; and discontinuous metal skids supported by said wall for guiding material from one conveyor to the other.

13. High temperature equipment comprising a hot chamber; a movable endless conveyor inside said chamber; and a power transmission for delivering power to said conveyor at a plurality of spaced points; said power transmission including spaced sprockets outside said chamber; a chain connecting said sprockets, and yielding take-up means in the tension or load transmitting reach of said chain.

14. High temperature equipment for operation above 1400° F., comprising refractory and insulating walls defining a single unobstructed enclosure in the shape of a rectangular parallelo-piped transverse support and drive shafts near the ends of said enclosure having reduced ends passing out through said walls, an endless conveyor driven and in part supported by said shafts, skids partly supporting both reaches of said conveyor, and cross bars mounted in said side walls and supporting at least one of said skids, positive drive means for rotating the shaft at the discharge end of the conveyor, and automatic means for delivering to the shaft at the receiving end of the conveyor a predetermined torque independent of speed and less than that necessary to move the entire conveyor.

55 15. High temperature equipment for operation above 1400° F., comprising refractory and insulating walls defining a single unobstructed enclosure, transverse shafts near the ends of said enclosure having reduced ends passing out through said walls, an endless conveyor driven by said shafts, positive 60 drive means for rotating the shaft at the discharge end of the conveyor, automatic means for delivering to the shaft at the receiving end of the conveyor a predetermined torque independent of speed and less than that necessary to move the entire conveyor, means 65

for adjusting the tension of the conveyor as a whole, and means for adjusting the torque delivered to the shaft at the receiving end.

16. High temperature equipment for operation above 1400° F., comprising refractory and insulating walls defining a single unobstructed enclosure, transverse shafts near the ends of said enclosure having reduced ends passing out through said walls, an endless conveyor driven by said shafts, positive drive means for rotating the shaft at the discharge end of the conveyor, automatic means for delivering to the shaft at the receiving end of the conveyor a predetermined torque independent of speed and less than that necessary to move the entire conveyor, and means for adjusting said automatic means to vary the torque. 70 75 80

17. High temperature equipment for operation above 1400° F., comprising refractory and insulating walls defining a single unobstructed enclosure, transverse shafts near the ends of said enclosure having reduced ends passing out through said walls, an endless conveyor driven by said shafts, positive drive means for rotating the shaft at the discharge end of the conveyor, and automatic means for delivering to the shaft at the receiving end of the conveyor a predetermined torque independent of speed and less than that necessary to move the entire conveyor. 85 90 95

18. High temperature equipment for operation above 1400° F., comprising refractory and insulating walls defining a single unobstructed enclosure, transverse support and drive shafts near the ends of said enclosure having reduced ends passing out through said side walls, an endless conveyor driven and in part supported by said shafts, skids partly supporting both reaches of said conveyor, and cross bars mounted in said side walls and supporting at least one of said skids.

19. High temperature equipment comprising an enclosed chamber hotter than 1,400° F. and interiorly unobstructed so that the gaseous contents comprise one substantially unitary and uninterrupted mass, an endless conveyor entirely enclosed in said chamber, said conveyor itself constituting the main obstruction in said chamber, a skid supporting the upper load-carrying reach of said conveyor, cross bars mounted in the chamber walls and supporting said skid, a similar skid for the lower slack reach of said conveyor, drive shafts at both ends of said conveyor, each drive shaft having reduced ends projecting out through the chamber walls to receive power, power means for rotating the drive shaft at the discharge end of said conveyor at a given speed regardless of the torque needed, and a transmission for delivering to the drive shaft at the receiving end of said conveyor a given torque independent of speed and less than that nec- 110

130

essary to move the entire conveyor, said transmission being driven from said same power means.

20. High temperature equipment comprising an enclosed chamber hotter than 1,400° F. and interiorly obstructed so that the gaseous contents comprise one substantially unitary and uninterrupted mass, an endless conveyor entirely enclosed in said chamber, said conveyor itself constituting the main obstruction in said chamber, a skid supporting the upper load-carrying reach of said conveyor, cross bars mounted in the chamber walls and supporting said skid, and a similar skid for the lower slack reach of said conveyor.

In testimony whereof I hereunto affix my signature.

FRANK A. FAHRENWALD.
